UNITED STATES PATENT OFFICE.

JAMES M. COLEMAN, OF MONTREAL, QUEBEC, CANADA, ASSIGNOR OF ONE-FOURTH TO
JAMES W. COLEMAN, OF MONTREAL, CANADA.

CAR-END REINFORCEMENT.

1,348,482.

Specification of Letters Patent.

Patented Aug. 3, 1920.

Application filed August 26, 1918. Serial No. 251,465.

To all whom it may concern:

Be it known that I, JAMES M. COLEMAN, a citizen of the United States, and resident of the city of Montreal, in the Province of Quebec and Dominion of Canada, have invented certain new and useful Improvements in Car-End Reinforcements, of which the following is a full, clear, and exact description.

10 This invention relates to improvements in car end stiffeners and the object of the invention is to provide a simple, durable and efficient means for stiffening the ends of box cars to resist internal pressure.

15 A further object is to provide means for securely connecting the ends of box cars to the sides.

The device consists essentially of a truss construction secured inside the end of a box car close to the roof and connected to the vertical framing of the end to support the same and hold the ends against bulging when the load shifts with the stopping and starting of the car. The truss construction 25 may be of various forms and may include the car end as part of the truss or may be entirely separate therefrom.

In the drawings which illustrate the invention:—

30 Figure 1 is a fragmentary cross-sectional view of a car looking toward the end and shows one form of stiffener in place.

Figs. 2, 3 and 4 are fragmentary horizontal sectional views of a car showing various forms of stiffener in position.

Figs. 5 and 6 are plan views of an end of a stiffener showing modified constructions which may be applied to any of the forms shown in Figs. 2, 3 or 4.

40 Referring more particularly to the drawings, 11 designates the end and 12 the side of a box car and 13 the roof. In ordinary car construction the end is provided with a pair of vertical frame members 14 disposed 45 symmetrically about the center line. In order to stiffen the end and enable it to resist the internal thrust of shifting loads when the car stops or starts a pair of supplementary frame members 15 are provided

50 outside the members 14. These supplementary members are usually in the form of metal beams of I or Z sections which are rigidly secured at their lower ends to the under-frame of the car. These supplementary members are unattached at their upper

extremities because there is no sufficiently strong framing at the roof of a wooden car to which they may be attached and they are intended to resist outward (or inward) pressure by their inherent rigidity.

According to this invention the upper extremities of these supplementary frames are secured to a truss which is connected to the end and sides of the car. The truss comprises a compression member 16 which may 60 be an angle or a channel, and a tension member which may be the end of the car or a separate member 17 as shown in Fig. 4. The center part of the compression member is spaced away from the end of the car and 65 from the tension member by a filler 18. The compression member is inclined from the central part toward the end of the car and at its extremities is bent to form feet 19 which are bolted to the sides of the car. 70 The supplementary members 15 are secured to the central part of the compression member 16 by bolts 20 which pass through the filler 18.

In the form shown in Fig. 2 the inclination of the compression member is such that it touches the car end very close to the sides so that if bolted to the car end at all there is room for only one bolt. In the form shown in Fig. 3 the inclination is greater so 80 that portions 21 are provided at each side of the car which bear against and may be securely bolted to the car end. In the form shown in Fig. 4 a straight-line tension member 17 is riveted at its ends to the compression member adjacent the feet 19. This tension member preferably takes the form of a flat strap of metal. It is immaterial so far as the compression member is concerned whether the tension member is an 85 end carline 23, as in Figs. 2 and 3, or a separate member 17, as in Fig. 4.

In order to stiffen and support the feet 19, gusset plates 22 may be riveted between the feet and adjacent portions of the compression member. The gusset plate is applicable to any of the forms shown in Figs. 2, 3 and 4.

The operation of the device is extremely simple. The compression member alone or 105 with the tension member 17 may be inserted in either new or old cars with equal facility. When the load in a car exerts outward pressure on the ends this load is transmitted in part to the compression member 16 by 110

the members 14 and 15. The force exerted tends to straighten the compression member which straightening is resisted by the tension member whether the same is in the 5 form of a special member 17 or merely the car end 11. The secure attachment of the feet of the compression member to the sides of the car prevent the stiffener being moved bodily outward when it resists the tendency 10 to straighten. The gusset plates 22 strengthen the structure at the sharp turn where the feet join the body of the member. If desired feet formed integral with the compression member may be omitted entirely 15 and gusset plates 22^a provided having down-turned flanges or feet which may be bolted to the sides of the car. The stiffener serves also to hold the sides of the car against spreading away from one another.

20 Having thus described my invention, what I claim is:—

1. An inside end stiffener for box cars located above and separate from the under frame comprising a one piece compression member arched away from the car end in its 25 central portion and connected to the car end toward its extremities.

2. A device according to claim 1 having feet attached to the sides of the car.

30 3. An inside end stiffener for box cars, located above and separate from the under frame, comprising a compression member arched away from the car end in its central portion and connected to the car end toward its extremities, feet attached to the sides of the car, and a filler spacing its central portion away from the car end.

35 4. An inside end stiffener for box cars comprising in combination with external vertical end frames a compression member arched at its center away from the car end and connected at its center to said vertical frame members and at its ends to the car end and to the car sides.

5. In car construction, the combination 45 with vertical end frame members of a truss connected at its center to the upper extremities of said members, comprising an arched compression member and a tension member forming part of the car frame proper.

50 6. A device according to claim 5, in which the compression member is arched inwardly from the car end in its central portion and the part of the car frame forming the tension member of the truss is an end carline.

55 7. In car construction, the combination with vertical end frame members, of a truss connected at its center to the upper extremities of said members, said truss being connected to the car sides, the truss comprising 60 a compression member arched inwardly from the car end in its central portion, and an end carline secured to the ends of said compression member and forming a tension member, and a filler interposed between the 65 compression and tension members, and bolts connecting the vertical members and truss together and holding said filler.

8. An inside end stiffener for box cars comprising a tension member and a compression member connected together at their extremities, a filler spacing said members apart at the center, feet at the ends of the stiffener attachable to the sides of a car, and gusset plates extending between the feet 75 and adjacent portions of the stiffener.

9. An inside end stiffener for cars located above and separate from the under frame, comprising a one piece compression member arched away from the car end in its central 80 portion and connected to the car end toward its extremities, and means at the ends of the compression member connected to the car sides.

In witness whereof I have hereunto set 85 my hand.

JAMES M. COLEMAN.
